Primary Examiner — Mitchell Siegel(74) *Attorney, Agent, or Firm* — Sand & Sebolt(57) **CLAIM**

The ornamental design for a golf club carrying device, as shown and described.

DESCRIPTION

FIG. 1 is a perspective view of a golf club carrying device; FIG. 2 is a side elevational view thereof; FIG. 3 is a top plan view thereof; FIG. 4 is a bottom plan view thereof; FIG. 5 is a perspective view of a second embodiment of a golf club carrying device as disclosed in FIG. 1; FIG. 6 is a side elevation of FIG. 5; FIG. 7 is a top plan view of FIG. 5; and, FIG. 8 is a bottom plan view of FIG. 5. The broken line showing of a pair of golf clubs in FIGS. 1 and 5 is included for the purpose of illustrating and forms no part of the claimed design.
